UNITED STATES PATENT OFFICE.

WILLIAM A. WHITCOMB, OF MILLINOCKET, MAINE.

BARKING-MILL.

1,120,636.

Specification of Letters Patent.

Patented Dec. 8, 1914.

Application filed May 8, 1914. Serial No. 837,327.

To all whom it may concern:

Be it known that I, WILLIAM A. WHITCOMB, a citizen of the United States, residing at Millinocket, in the county of 5 Penobscot and State of Maine, have invented an Improvement in Barking-Mills, of which the following is a specification.

This invention relates to barking-mills for removing bark from logs or blocks of wood, 10 which are used in the production of pulp in the manufacture of paper, and is an improvement upon the barking-mill forming the subject-matter of an application for Letters Patent #802,586, filed November 24, 15 1913, of Garret Schenck. In the machine of said application the blocks of wood are tumbled while in a dry state, and by the tumbling action the bark is removed from the blocks, and during the tumbling operation 20 the detached dry bark is segregated from the blocks by gravity. Said machine is a wide step in advance over prior machines of this character, and has resulted in a substantial saving in the expense of preparing the blocks for the grinders, and the 25 wood is not chipped, scraped or cut off of the block, and the bark, which is removed is in a dry state and has a value for fuel. In some instances the blocks are smeared with 30 dirt and sometimes small pieces or patches of bark still cling to the blocks which it is desirable to remove, and sometimes the bark which has been removed sticks to the blocks, and I have discovered that by washing the 35 debarked or substantially debarked blocks with water the dirt and loose pieces of the bark may be removed, and the blocks thus better and more completely prepared for presentation to the grinders.

40 This invention has for its object the provision of means for washing the blocks after they have been debarked or substantially debarked by the apparatus of the aforesaid application and the association of 45 said means with said apparatus whereby the operation of debarking and of washing becomes a continuous one.

My invention, in so far as its method is involved, consists in debarking the blocks 50 while in a dry state by a tumbling action, segregating the detached bark from the blocks by gravity during the debarking or tumbling operation, and then washing the debarked or substantially debarked blocks, 55 the entire operation being a continuous one.

One form of apparatus by which the pres-

ent invention is carried out, which is here shown for illustration, comprises a rotatable tumbling-chamber arranged in a slightly inclined position into which the 60 blocks are delivered at one end and from which they are discharged at the other end, said chamber having openings at intervals to admit of the escape of the detached pieces of bark, which are segregated from the 65 blocks and caused to escape by gravity, and another rotatable tumbling-chamber arranged in continuation of the aforesaid chamber at the discharge end thereof, into which the blocks are delivered at one end 70 and from which they are discharged at the other end, said chamber being partially submerged in a tank of water, so that the blocks are tumbled in the presence of water, and the dirt and the small pieces of bark are 75 removed, thus cleansing the blocks and preparing them in the best possible condition for presentation to the grinders, the apparatus being constructed and arranged in such manner that the entire operation is a 80 continuous one.

Figure 1 is a side elevation of a barking-mill embodying this invention. Fig. 2 is a left-hand end elevation of the same. Fig. 3 is a transverse vertical section through the 85 wet tumbling-chamber. Figs. 4 and 5 are plan and sectional views of a portion of the mill, illustrating the preferred form of driving-means for the wet tumbling-chamber. Figs. 6 and 7 are plan and sectional 90 views of a like portion of the mill, illustrating another modified form of driving-means for the wet tumbling-chamber.

In the embodiment of my invention shown in Fig. 1, the dry tumbling-chamber and the 95 operating-means are substantially as shown in the aforesaid application, and consists of three cylindrical pipe-sections 10, 12 and 14, although any other number may be employed. Each section may be composed of 100 several short cylindrical sections of pipe, telescopically arranged and secured together, or they may be otherwise constructed. The several pipe-sections 10, 12 and 14 are arranged in alinement to enable the blocks 105 to move from one to the next section throughout the entire length of the dry tumbling-chamber, and said sections are arranged in a slightly inclined position to facilitate such movement of the blocks, and 110 they are separated from each other short distances to provide annular openings for

the escape of the dry pieces of bark which are removed from the blocks, but it will be obvious that openings may be otherwise formed at intervals for this purpose. The 5 interior of the pipe-sections are preferably made smooth, which admits of the blocks being easily moved along in a direction toward the exit, and prevents clogging of the blocks and chipping of the wood. In said 10 dry chamber, as represented in Fig. 1, the right-hand end thereof is the inlet, and at said end an annular plate 18 is secured having a center-hole 20, through which the wood blocks are fed in. Said plate partially 15 closes the end of the pipe-section to which it is attached, and serves as a retaining-plate for the blocks.

The left-hand end of the dry-chamber is the exit and at said end an annular plate 22 20 is provided, having a center-hole 24 through which the wood blocks are discharged. Said plate partially closes the end of the pipe-section to which it is attached, and serves as a retaining-plate for the blocks. Said plate 25 22 is not attached directly to the end of the pipe-section as is the plate 18, but is supported in fixed position in front of said pipe-section by brackets 26, thereby providing an opening between the end of the piping 30 section and the plate for the escape of the pieces of dry bark, said opening being substantially the same as the openings before described, which are arranged at intervals along the chamber. Each pipe-section has 35 arranged on its circumference flanged rings 30, there being two such rings shown on each pipe-section which are arranged in parallel relation, and disposed near the ends of the sections, and said rings rest upon flanged 40 rollers 32 secured to shafts 33, which are positively rotated. The weight of the pipe-sections, particularly when loaded with the wood blocks, is sufficient to enable them to be rotated by frictional engagement with the 45 rotating rolls, although in lieu of frictional gearing such as described any other form of gearing may be employed for rotating the pipe-sections. As here shown, it will be noted that the pipe-sections are 50 made independent of each other and are, therefore, independently rotatable, but ordinarily they will be rotated in unison, as they are rotated by means common to all of them, but independent rotation of the sections, instead of being a disadvantage, is an advantage as the blocks which extend across the 55 openings are so interlocked with other blocks in the sections that independent movement of one section relative to the other will accelerate the tumbling of the blocks.

At the discharge end of the dry tumbling-chamber the wet tumbling-chamber is arranged, it being made as a pipe-section 40 composed of several short cylindrical sections of pipe telescopedically arranged and se-

cured together, or it may be otherwise constructed. The interior of this pipe-section is preferably smooth like the aforesaid pipe-sections, which admits of the blocks being easily moved along therein. The right-hand 70 end of the pipe-section is the inlet and the left-hand end is the outlet, and the inlet is arranged in front of the outlet of the last section of the dry tumbling-chamber to receive the debarked or substantially debarked 75 blocks which emerge from said chamber. At the left-hand end of the wet tumbling-chamber an annular plate 41 is provided having a center-hole 42 with a longitudinally extended flange 43 thereat. Said pipe-section 40 has arranged on its circumferences flanged rings 45, 46, there being two such rings here shown, which are arranged in parallel relation and disposed near the ends of the section and rest upon flanged rollers 47 secured to shafts 48 which are positively rotated. The weight of the section, particularly when loaded with blocks, is usually sufficient to enable it to be rotated by frictional engagement with the rotating rolls, 90 but in lieu of friction gearing such as described, other forms of gearing may be employed, as represented for instance in Figs. 4 to 7, and should be so employed if any trouble from slipping arises. Said pipe-section 40 is arranged in a tank 50 which is arranged to be supplied with water by a pipe 51 or other means to a predetermined level, and has an outlet at 52 and when thus arranged in said tank it is partially submerged 100 so that the blocks at the bottom thereof are tumbled in the water. At the outlet of the wet tumbling-chamber a conveyor is here shown at 60, which receives upon it the washed blocks and by which 105 they are carried up a chute for delivery to any desired place or places, as for instance, they may be delivered to a room containing the grinders, or may be delivered to a room containing a splitter, or may be delivered 110 elsewhere.

From the general description above, it will be understood that many of the structural features of the apparatus may be altered without departing from the spirit and 115 scope of my invention.

In Figs. 4 and 5 a sprocket-chain driving-means is illustrated which I have found effective, and in Figs. 6 and 7 a toothed gear driving-means is illustrated, these methods 120 being among the many which may be employed in lieu of frictional gearing shown in Figs. 1 to 3.

The operation of the mill is as follows: While the tumbling-chamber is rotating the 125 wood blocks are fed in through the center-hole in the retaining-plate at the upper end and are caused to tumble over and upon each other, and against the wall of the chamber and to move along to the lower 130

end thereof, where they are discharged through the center-hole in the retaining-plate thereat, and while being tumbled and moved along the bark is removed in a dry state from them, and the pieces of dry bark fall by gravity through the openings, being thus segregated from the blocks. The dry debarked or substantially debarked blocks then pass continuously from the dry tumbling-chamber to the wet tumbling-chamber, whereupon they are caused to tumble over and upon each other and against the wall of the chamber and to move along to the outlet end thereof to be discharged upon a conveyer and while tumbled about in said wet tumbling-chamber they are washed and cleansed.

I claim:—

1. The process herein described of debarking blocks which consists in removing the bark from the blocks while in a dry state by a tumbling action, segregating the detached bark from the blocks by gravity, during the debarking operation, and washing and thereby cleaning the debarked or substantially debarked blocks, the entire operation being continuous.

2. The process herein described of debarking blocks which consists in subjecting the blocks while in a dry state to a tumbling action, thereby to remove the bark therefrom, and segregating the detached bark from the blocks by gravity at intervals during the tumbling action, then further removing the bark from the blocks in the presence of water by a tumbling action and segregating the bark thus detached from the blocks, the entire operation being continuous.

3. A barking-mill consisting of a rotatable dry tumbling-chamber arranged to receive and tumble the blocks in a dry state, and a rotatable wet tumbling-chamber located at the discharge end of said dry chamber in continuation thereof and arranged to receive and tumble the blocks in a wet state, substantially as described.

4. A barking-mill consisting of a rotatable dry tumbling-chamber arranged to receive and tumble the blocks in a dry state and having openings for the escape of the dry bark, and a rotatable wet tumbling-chamber located at the discharge end of said dry chamber in continuation thereof and arranged to receive and tumble the blocks in a wet state, substantially as described.

5. A barking-mill consisting of a rotatable dry tumbling-chamber arranged to receive and tumble the blocks in a dry state and having openings for the escape of the dry bark, and another rotatable tumbling-chamber located at the discharge end of said dry chamber in continuation thereof, and a tank for containing water in which said chamber is partially submerged, said

chamber being arranged to receive and tumble the blocks in a wet state, and means arranged to provide for the supply and escape of water to and from said tank, substantially as described.

70

6. A barking-mill consisting of a rotatable dry tumbling-chamber arranged to receive and tumble the blocks in a dry state and having openings for the escape of the dry bark, and another rotatable tumbling-chamber located at the discharge end of said dry chamber in continuation thereof, and a tank for containing water in which said chamber is partially submerged, said chamber being arranged to receive and tumble the blocks in a wet state, and frictional driving-means co-extensive with all said chambers for rotating them and permitting independent rotation thereof, substantially as described.

75

7. In a barking-mill, the combination of a plurality of cylindrical open-ended rotatable pipe-sections arranged in alinement and in a slightly inclined position having open spaces arranged at intervals, and another open-ended rotatable pipe section arranged at the discharge end of the aforesaid pipe-sections, a tank for containing water in which said last-named pipe-section is partially submerged, and driving means for the sections, substantially as described.

80

8. In a barking-mill, the combination of a plurality of open-ended pipe-sections arranged in alinement and in a slightly inclined position, separated from each other short distances to provide open spaces between them, and another open-ended pipe-section arranged at the discharge end of the aforesaid pipe-section, a tank for containing water in which said pipe-section is partially submerged, and a common driving-means to rotate all said sections, with which they are frictionally connected, permitting independent rotation thereof, substantially as described.

100

9. In a barking-mill, the combination of a plurality of open-ended pipe-sections arranged in alinement and in a slightly inclined position and separated from each other to provide open spaces between them, and another open-ended pipe-section arranged at the discharge end of the aforesaid pipe-section, and at a lower elevation, a tank for containing water in which said last-named pipe-section is partially submerged, and driving means for said sections, substantially as described.

110

10. A barking-mill consisting of a rotatable dry tumbling-chamber arranged to receive and tumble the blocks in a dry state, and having at its exit an annular retaining-member, and a discharge opening immediately in rear thereof, a rotatable wet tumbling-chamber located at the discharge end of said dry-chamber, but at a lower eleva-

125

130

tion, a tank containing water in which said last-named tumbling-chamber is partially submerged, over the top of which said annular retaining-member extends, and driving-
5 means for said chambers, substantially as described.

In testimony whereof, I have signed my

name to this specification, in the presence of two subscribing witnesses.

WILLIAM A. WHITCOMB.
